UNITED STATES PATENT OFFICE

WILLIAM J. MCSPEDON, JR., OF NEPERA PARK, NEW YORK

SAFETY GAS COCK

Application filed April 5, 1930. Serial No. 443,743.

This invention relates to gas cocks and aims particularly to provide a safety gas cock which is normally locked in its closed position so that the same may not be accidentally opened but which may be opened with facility when desired.

The primary object of the invention is to provide a simple and efficient safety gas cock which will be positive in its action and which may be economically manufactured.

A further object of the invention is to provide a safety gas cock in which the operating handle is secured to the plug stem which carries a spring-held lock normally adapted to abut against a plug or projection provided on the stem for locking the cock in its closed position, the locking device being movable to release the same from engagement with the lug on the stem when it is desired to open the gas cock.

Still another object of the invention is to provide a locking device which is conveniently engageable by the thumb of the user, to release the lock, while the handle is grasped by the fingers, for opening the gas cock whereby the gas cock may be unlocked and opened by a single operation of the hand.

Yet another object of the invention is to provide a locking device which will operate automatically to lock the gas cock in its closed position when the gas has been turned off.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

Fig. 1 is a front elevation of the gas cock showing the locking device in operation;

Fig. 2 is a vertical sectional view substantially on the line 2—2 of Fig. 1;

Fig. 3 is a view similar to Fig. 2 showing the position of the locking device when about to release the handle, and as the parts appear when the gas cock is opened;

Fig. 4 is a top plan view showing the body with the locking member removed;

Fig. 5 is a detail view partly in section of the locking member; and

Fig. 6 is a bottom plan view of the locking member shown in Fig. 5.

Referring more particularly to the drawings, the safety gas cock in this instance includes a body 10 having a conical bore 11 extending vertically through the body. An elongated conical plug or stem 12 is positioned in the bore, and this plug 12 is provided with the usual port 13 adapted to register with the inlet portion 14 and outlet portion 15 of the body 10. The plug 12 is held to its seat by means of a locking washer 16 and spring 17, and the lower end of the plug 12 is preferably equipped with a suitable set screw 18.

The plug 12 is provided with an outwardly extending portion 19 adjacent to its upper end, and an operating handle 20 is secured to the outwardly extending portion 19, the handle 20 being secured upon the outwardly extending portion 19 in any suitable manner as for instance by means of the end screw 21.

Means are provided to lock the handle 20 in its closed position, and in this instance the locking means include a substantially cylindrical locking member 22 positioned upon the upper part of the stem or plug 12 which extends beyond the body portion 10. This locking member 22 has a portion of its wall removed at the base as seen at 23, and the end faces 24 and 25 respectively of the cut away portion 23 are adapted to engage a lug 26 formed at the upper part of the body member 10, when the gas cock is in its closed position, the gas cock being thus securely locked in said closed position. To permit the gas cock to be opened, the semi-cylindrical wall 27 at the base of the locking member 22 is formed with a semi-annular groove 28, which groove is adapted to receive the lug 26 when the locking member 22 has been depressed.

Thus when the locking member has been

pressed down to align the groove 28 with the lug, the gas cock may be opened by means of the handle 20.

Resilient means are provided to mount the locking member upon the upper portion of the plug 12. In this instance the head portion 29 of the plug 12 is provided with a cylindrical extension 30 extending upwardly within the interior of the cylindrical locking member 22. This extension 30 is of such diameter that an annular chamber 31 is formed within the locking member, above the plug head 29. A coil spring 32 is provided in the chamber 31, and this spring 32 is adapted to be compressed by means of a set screw 33 threaded within the chamber 31 as indicated at 34. This set screw 33 is provided with a depending guiding stem 35 adapted to traverse a guiding recess 36 provided in the cylindrical extension 30. The spring 32 thus normally acts against the base of the screw threaded member 33 to hold the lock member in its upward position, with the shoulder or face 25 in engagement with the lug 26, in which position of the parts the gas cock is positively locked in closed position. The screw threaded member 33 is provided with a cap or thumb piece 36 for use in depressing the locking member 22 against the force of the spring 32 to release the shoulder 25 from its engagement with the lug 26 so that the handle 20 may be manipulated to turn the plug 12, the lug 26 at this time being traversed by the internal groove 28 of the locking member. The side wall of the cylindrical locking member 22 has an upwardly extending recess 37 in alignment with the neck portion 38 of the plug head 29, this recess 37 affording a limit of travel for the locking member to its plug releasing position.

The present safety gas cock is operable with great facility, it being simply necessary for the user to apply the thumb of say the right hand upon the cap 36, to depress the locking member 22, whereupon the handle 20 may be manipulated to open the gas cock. When it is desired to turn off the gas, the handle 20 is simply moved to the normal closed position of the gas cock, whereupon the lower grooved portion 28 of the locking member will be released from the shoulder 26 and the spring 32 will force the locking member upward so that the shoulder 25 abuts against the lug 26, thus automatically locking the gas cock in its closed position.

While the present invention has been shown as applied to a more or less conventional type of gas cock, it is to be understood that the present safety arrangement is applicable to many other types of valves or the like, the safety device being capable of a wide range of use in this respect.

The hereinabove described construction admits of considerable modification without

departing from the invention; therefore, it is the wish not to be limited to the precise arrangements shown and described, which are aforesaid, by way of illustration merely. In other words, the scope of protection contemplated is to be taken solely from the appended claims, interpreted as broadly as is consistent with the prior art.

What is claimed as new, is:

1. A safety gas cock or the like including a body having a bore therein, a plug seated in said bore, said body having inlet and outlet passages, and said plug having a port adapted to afford communication between said passages, an operating handle secured to the upper part of said plug, means to lock said plug in position to close communication between said inlet and outlet passages, said means including a locking member mounted upon the upper part of said plug, said locking member having a cut-out portion at its lower end, a lug extending outwardly from the upper part of said body, a side wall of the cut-out portion of said locking member being adapted to abut against said lug to normally lock said plug in closed position, said locking member being compressible to release the lug abutting portion of said locking member and permit partial rotation of said locking member and hence said plug, to open the gas cock, and resilient means to automatically restore said locking member to its normal upward position when the gas cock is turned to its closed position.

2. A safety gas cock or the like including a body having a bore therein, a plug seated in said bore, said body having inlet and outlet passages, and said plug having a port adapted to afford communication between said passages, said plug having an outwardly extending portion at its upper end, an operating handle on said outwardly extending portion, means to lock said plug in position to close communication between said inlet and outlet passages, said means including a substantially cylindrical locking member mounted upon the upper part of said plug, said locking member having a cut-out portion at its lower end, a lug extending outwardly from the upper part of said body, a side wall of the cut-out portion of said locking member being adapted to abut against said lug to normally lock said plug in closed position, said locking member having an internal groove and being compressible to align said groove with said lug, whereby to release the lug abutting portion of said locking member and permit partial rotation of said locking member and hence said plug, to open the gas cock, and resilient means to automatically restore said locking member to its normal upward position when said lug is released from said internal groove on manipulation of the gas cock to its closed position, said resilient means includ-

ing a coiled spring within the upper part of said cylindrical locking member, an adjustable cap screw-threaded at the top of said locking member, said spring normally acting against said cap to hold said locking member in its operative position.

3. A safety gas cock or the like including a body having a bore therein, a plug seated in said bore, said body having inlet and outlet passages, and said plug having a port adapted to afford communication between said passages, said plug having an outwardly extending portion at its upper end, an operating handle on said outwardly extending portion, means to lock said plug in position to close communication between said inlet and outlet passages, said means including a substantially cylindrical locking member mounted upon the upper part of said plug, said locking member having a cut-out portion at its lower end, a lug extending outwardly from the upper part of said body, a side wall of the cutout portion of said locking member being adapted to abut against said lug to normally lock said plug in closed position, said locking member being depressible to release the lug abutting portion of said locking member and permit partial rotation of said locking member and hence said plug, to open the gas cock, resilient means to restore said locking member to its normal upward position when the gas cock is turned to its closed position, said resilient means including a coiled spring within the upper part of said cylindrical locking member, an adjustable cap screw-threaded at the top of said locking member, said spring seating against said plug and normally acting against said cap to maintain said locking member in locking position.

4. A safety gas cock or the like including a body having a bore therein, a plug seated in said bore, said body having inlet and outlet passages, and said plug having a port adapted to afford communication between said inlet and outlet passages, said means including a substantially cylindrical locking member mounted upon the upper part of said plug, said locking member having a cut-out portion at its lower end, a lug extending outwardly from the upper part of said body, a side wall of the cut-out portion of said locking member being adapted to abut against said lug to normally lock said plug in closed position, said locking member having an internal groove and being depressible to align said groove with said lug, whereby to release the lug abutting portion of said locking member and permit partial rotation of said locking member and hence said plug, to open the gas cock, and resilient means to automatically

restore said locking member to its normal upward position when said lug is released from said internal groove on manipulation of the gas cock to its closed position, said resilient means including a coiled spring within the upper part of said cylindrical locking member, an adjustable cap screw-threaded at the top of said locking member, said spring normally effective between said cap and said plug to maintain said locking member in operative position, said plug including a neck portion between the head of the plug and said outwardly extending portion, and said locking member having a recessed portion above said neck to define the limit of travel of said locking member to its lug releasing position.

In testimony whereof I hereby affix my signature.

WILLIAM J. McSPEDON, JR.
